UNITED STATES PATENT OFFICE.

JOHN W. FAESSLER, OF MOBERLY, MISSOURI.

METHOD OF EXTRACTING MANDRELS FROM BOILER-TUBE EXPANDERS.

1,133,014.

Specification of Letters Patent. Patented Mar. 23, 1915.

Application filed October 9, 1912. Serial No. 724,835.

To all whom it may concern:

Be it known that I, JOHN W. FAESSLER, a citizen of the United States, and resident of Moberly, Randolph county, Missouri, have invented certain new and useful Improvements in Methods of Extracting Mandrels from Boiler-Tube Expanders, of which the following is a specification containing a full, clear, and exact description, reference being had to the accompanying drawings, forming a part hereof.

My invention relates to an improved method of extracting mandrels from boiler tube expanders, and consists in the novel 15 steps of procedure hereinafter described and specifically pointed out in the appended claims.

The object of my invention is to provide an improved method of extracting mandrels from sectional boiler tube expanders, in order that the time of the operator will be greatly economized and the mandrel will be promptly extracted without injury to either the mandrel or the sections of the expander.

Heretofore the mandrels of sectional boiler tube expanders have been extracted by delivering side-wise blows of a hand hammer upon the side of the mandrel in order to loosen the same, and this is what I term the "hand" method; but the described "hand" method has not been satisfactory, for the reason that it occupied a great deal of the operator's time and also injured the mandrel and the sections of the expander.

Referring again to the drawings: The figure is a sectional side elevation of a portion of a boiler tube with a sectional expander therein having a mandrel, and illustrating my method of extracting the mandrel.

The numeral 1 indicates the usual boiler tube located in the tube sheet 2, and 3 the sectional tube expander located in said boiler tube, 4 being the usual mandrel to be 45 forcibly driven between the sections of the expander during the operation of expanding the tube.

In order to extract the mandrel without injuring either the mandrel or the sections 50 of the expander, I need not strike the mandrel 4, but on the other hand I strike the projecting ends of the sections 5 of the expander with any suitable tool and thereby virtually drive them off the mandrel.

For the purpose of striking the expander sections 5 to detach the mandrel 4, I pref-

erably make use of a sleeve 6 adapted to loosely embrace the mandrel and having an arm 7 extended laterally therefrom to receive the impacts of a suitable hammer so that part of the force of each impact will be imparted to the said sections 5 of the expander to loosen them from the mandrel and another part of the force of the impact will be imparted to the side of the mandrel to 65 loosen the mandrel without damaging it. The said arm 7 is preferably shaped so that its extractor 3 extends in a plane parallel with the sleeve. The hammer which I prefer to use is a common pneumatic hammer 8, 70 the tool 9 of which is provided with a stem 10 which fits into the end of the body of the hammer.

The numeral 11 designates a rubber ring which embraces the sections 5 of the expander to yieldingly hold them in place. When assembled, these sections each engage one of the faces of the tapered polygonal portion 12 of the mandrel and their outer surfaces combined form substantially a 80 shoulder of the proper shape to expand the tube 1 in the usual manner.

To extract the mandrel 4 the sleeve 6 is placed over the mandrel, as shown, and the tool 9 of the pneumatic hammer is placed 85 against the rounded end 13 of the extractor arm 7 and said hammer is started in the usual manner and caused to exert blows or shocks to the said arm, thereby driving the expander sections 5 away from the mandrel 90 4 and loosening the same. Each impact of the hammer forces the end of the sleeve 6 against the expander sections 5 and at the same time strikes a side blow against the said mandrel 4 and thereby also loosens the 95 same. In some cases I may place the pneumatic hammer 8 directly against the outer end of said sleeve 6 and thereby simultaneously loosen all of the extractor sections from the mandrel.

I claim:

1. The herein described method of extracting mandrels from boiler tube expanders, which consists in delivering a series of blows (or shocks) upon the expander sections, and thereby bodily forcing the expander from the mandrel and simultaneously impacting the side of the mandrel with a tool separate from said mandrel.

2. The herein described method of extracting mandrels from sectional boiler tube expanders, which consists in simultaneously

delivering a series of blows (or shocks) upon the expander-sections, and thereby bodily forcing all of the sections of the expander from the mandrel and simultaneously impacting the side of the mandrel with a tool separate from said mandrel.

In testimony whereof, I have signed my

name to this specification, in presence of two subscribing witnesses.

JOHN W. FAESSLER.
